UNITED STATES PATENT OFFICE

DHANJISHAH BOMONJEE COOPER, OF SATARA, INDIA

CRUSHING MACHINE

Application filed February 14, 1929, Serial No. 339,993, and in Great Britain February 22, 1928.

This invention relates to crushing machines, and more particularly to sugarcane crushing mills and has for its object to provide improved forms of bearings for the 5 shafts of the crushing rollers which bearings prevent irregular working of the shaft, increase the life of the bearings, render the machine more efficient in operation and diminish the power required to drive the 10 machine.

The crushing machine according to the present invention comprises improved bearings for the crushing roller shafts which bearings are essentially characterized in that 15 the bearing bushes are of polygonal form externally and are mounted in correspondingly shaped seatings, so that they can be taken out from time to time as they become worn and replaced in a different angular position so as to present a new wearing surface to the shaft, and take up any play due to the wearing down of the bush. It is preferred to make the bushes and their 20 seatings of hexagonal form so that six new rubbing faces can be presented to the shaft at the point where the pressure produced by the crushing rollers is greatest. This arrangement is very advantageous where the machines are employed in places remote 25 from industrial districts and where the replacement of worn parts involves difficulty and delay.

In a sugar-cane crushing machine the crushing rollers are mounted vertically, and 30 in such a machine the upper polygonal shaped bushes are each preferably provided with an absorbent packing ring closely encircling the shaft, and an oil well above the said absorbent ring and in communication 35 with it through small oil ducts.

The lower bearing bushes of the crushing rollers are preferably closed at the bottom ends and provided with upwardly convexed bearing blocks which bear against the lower 40 ends of the shafts and support the said shafts endwise.

The upper and lower bearing bushes are 45 preferably provided with helical oil ducts on their inner surfaces extending downwardly from their upper ends in order to

ensure the passage of oil over the entire bearings and thus keep the bearings efficiently lubricated.

In order that the invention may be understood and ascertained it will be more fully 55 described with reference to the accompanying drawings as applied to a machine for crushing sugar-cane.

In the said drawings,

Figure 1 is a vertical central section of 60 a crushing machine provided with bearings according to the invention,

Figure 2 is a section on an enlarged scale of one of the upper bearing bushes shown in Figure 1,

Figure 3 is a plan of the bearing bush 65 shown in Figure 2,

Figure 4 is a section on an enlarged scale of one of the lower bearing bushes,

Figure 5 is a plan of the bearing bush 70 shown in Figure 4.

Referring to the accompanying drawings the sugar-cane crushing machine shown in Figure 1 is of known construction and comprises the usual crushing rollers 10 and 11 75 known as king and queen rollers, fast upon the vertically disposed shafts 12 and 13. The upper and lower ends of the shafts 12 and 13 are mounted respectively in bearings in the cover member 14 and base member 80 15 of the machine. The upper bearings for the shafts are each identical with one another, and comprise bearing bushes 16 which, in the example shown are of hexagonal shape externally and these bushes 85 have an easy fit in correspondingly shaped seatings so that they may be readily slipped out, partially turned and replaced so as to present a new wearing face to that side of the shaft which exerts the most intense 90 pressure upon the bush. The lower bearing bushes 17 are also of similar shape on their exteriors and fit into correspondingly shaped seatings for the above mentioned purpose.

The upper bearings 16 are each provided 95 with a packing washer 18 of absorbent material disposed in an annular recess 19 formed in the upper part of the bush. The top of the recess 19 is closed by an annular member 20 which is channelled to form an 100

oil well and has oil ducts 21 at the bottom permitting the oil to have access to the absorbent packing washer 18. The collar is secured in position on the bush by screws 22, and the inner surface of the bush is preferably provided with a helical channel 21a permitting oil to run down.

The lower bearings 17 are each closed at the bottom end as at 23 and provided with a block 24 having its upper surface convexed or spherical. This block is secured against rotation by pins 25. The lower ends of the roller shafts 12 and 13 are of convexed or spherical form, as at 26, and between the said shafts is a freely rotatable block 27 having its upper and lower surfaces convexed or spherical in shape. The convex blocks 24 and the double convex blocks 27 which are preferably of hardened steel support the shafts 12 and 13 endwise and permit them to rotate with a minimum of friction. The upper ends of the lower bearing bushes are bevelled as at 28 to form a recess for lubricating oil, and inner surfaces of these bushes are preferably provided with a helical groove which permits the oil to work downwardly over the entire inner surface of the bush and to have access to the friction surfaces of the blocks 24 and 27.

It may be noted that for mounting the axles of wheel-barrows it has been proposed to use a pair of bearing bushes each of which is cap-like form to fit over the ends of the axle, the exterior of the caplike bushes being of hexagonal form and fitting into a correspondingly shaped pocket or recess in the bearing blocks and I make no claim to such herein, also I do not claim broadly the double-convex blocks which support the shafts endwise.

I claim:

1. A bearing for the roller shafts of crushing machines comprising in combination, a solid bearing bush of polygonal shape externally and having an enlarged bore for a short length at one end thereof, a corresponding internally shaped polygonal seating on the machine, a pad of absorbent packing material adapted to be carried within the said enlarged bore and to closely encircle and engage the roller shaft and an oil well in communication with the said pad.

2. A bearing for the vertical roller shafts of crushing machines comprising in combination, a solid bearing bush of polygonal shape externally and having an enlarged bore for a short length at the top end thereof, a corresponding internally shaped polygonal seating on the machine, a pad of absorbent packing material adapted to be carried within and to fill the said enlarged bore and to closely encircle and engage the roller shaft and an annular channel shaped oil well secured over the said enlarged bore

having oil ducts communicating between the bottom of the channel and the said absorbent pad.

3. A bearing for the roller shafts of crushing machines comprising in combination, a solid bearing bush of hexagonal shape externally and having an enlarged bore for a short length at one end thereof, a corresponding internally shaped hexagonal seating on the machine, a pad of absorbent packing material adapted to be carried within the said enlarged bore and to closely encircle and engage the roller shaft and an oil well in communication with the said pad.

4. A bearing for the vertical roller shafts of crushing machines comprising in combination, a solid bearing bush of hexagonal shape externally and having an enlarged bore for a short length at the top end thereof, a corresponding shaped hexagonal seating on the machine, a pad of absorbent packing material adapted to be carried within and to fill the said enlarged bore and to closely encircle and engage the roller shaft and an annular channel shaped oil well secured over the said enlarged bore having oil ducts communicating between the bottom of the channel and the said absorbent pad.

In testimony whereof I have signed my name to this specification.
